UNITED STATES PATENT OFFICE

153,591

DESIGN FOR A CAN OR SIMILAR ARTICLE

George C. Erb, Forest Hills West, N. Y., assignor
to American Can Company, New York, N. Y., a
corporation of New Jersey

Application February 18, 1946, Serial No. 126,678

Term of patent 14 years

(Cl. D58—17)

To the Commissioner of Patents:

Be it known that I, George C. Erb, a citizen of the United States of America, residing at No. 90—15 63rd Avenue, Forest Hills West, in the county of Queens and State of New York, have invented a new, original, and ornamental Design for a Can or Similar Article, of which the following is a specification, reference being had to the accompanying drawing, forming a part thereof.

Fig. 1 is a perspective view of a can, showing my new design;

Fig. 2 is an edge view of the can cover removed from the can; and

Fig. 3 is a sectional view taken along line 3—3 of Fig. 1.

The characteristic features of my design reside in the portions shown in full lines.

I claim:

The ornamental design for a can or similar article, as shown and described.

GEORGE C. ERB.
